UNITED STATES PATENT OFFICE

117,948

DESIGN FOR A FOOTSTOOL OR SIMILAR ARTICLE

Mark K. Forman, Worcester, Mass., assignor of one-third to James E. Connor and one-third to John J. Sullivan, both of Worcester, Mass.

Application October 12, 1939, Serial No. 87,644

Term of patent 7 years

To all whom it may concern:

Be it known that I, Mark K. Forman, a citizen of the United States residing at Worcester, in the county of Worcester and State of Massachusetts, have invented a new, original, and ornamental Design for a Footstool or Similar Article, of which the following is a specification, reference being had to the accompanying drawing, forming part thereof.

Fig. 1 is a side view of a footstool or similar article showing my new design; and

Fig. 2 is an end view thereof.

I claim:

The ornamental design for a footstool or similar article, as shown.

MARK K. FORMAN.
